UNITED STATES PATENT OFFICE.

OSCAR H. PIEPER AND ALPHONSE F. PIEPER, OF ROCHESTER, NEW YORK.

SUPPORTING-BRACKET FOR ELECTRICAL INSTRUMENTS.

1,278,997.

Specification of Letters Patent. Patented Sept. 17, 1918.

Original application filed October 15, 1915, Serial No. 56,122. (Patent No. 1,211,752.) Divided and this application filed December 27, 1915, Serial No. 68,896. Renewed May, 27, 1918. Serial No. 236,924.

To all whom it may concern:

Be it known that we, OSCAR H. PIEPER and ALPHONSE F. PIEPER, both of Rochester, in the county of Monroe and State of New York, have invented certain new and useful Improvements in Supporting-Brackets for Electrical Instruments; and we do hereby declare the following to be a full, clear, and exact description of the same, reference 5 being had to the accompanying drawings, forming a part of this specification, and to the reference-numerals marked thereon.

This application is a division of our application for electric controlling mechanism, 15 Serial No. 56,122, filed October 15, 1915, and issued as Patent No. 1,211,752, dated January 9, 1917.

The present invention has for its purpose to afford a novel form of bracket or support 20 for electrically controlled instruments, such for instance as cauteries, hot air syringes, and the like, whereby the supply of electric current to the instrument is automatically cut off when the instrument is supported on 25 the bracket and not in use. A further purpose of the structure resides in the provision of a simple arrangement which can be manufactured at a reasonable cost and assembled readily, while at the same time making 30 it possible to easily position an instrument within the bracket or remove it therefrom. To these and other ends the invention consists in certain improvements and combinations of parts, all as will be hereinafter more 35 fully described, the novel features being pointed out in the claims at the end of the specification.

In the drawings:

Figure 1 is a view in front elevation showing 40 the application of the invention to an electric controlling mechanism with an instrument supported in its bracket;

Fig. 2 is a side elevation of the same;

Fig. 3 is a detail view in rear elevation of 45 the support on which the bracket is mounted;

Fig. 4 is a plan view of the support;

Fig. 5 is a sectional view taken centrally 50 of one of the brackets, and

Fig. 6 is a sectional view on line 6^a—6^a of 55 Fig. 5.

Similar reference numerals in the several figures indicate the same parts.

The invention may be carried out or applied in a number of different ways, and in 55 the present embodiment we have shown a

type of electric controlling mechanism, such as is employed in dental surgical work for governing the operation of different tools and instruments, comprising a casing or housing 1 and a movable door 2, which is 60 provided with a conduit or hollow supporting arm or carrier 3 having laterally extending branches upon which are mounted the various instrument brackets, and which is also provided with electrical conductors that 65 furnish a supply of current to the various instruments. The arm or carrier 3 is capable of being bodily removed from the housing 1 and to this end plug terminals *a* are 70 provided for the circuit wires inclosed in the arm, which project from the insulating plate *b* and are received in corresponding jacks or sockets *a'* in the housing. This means of mounting the arm enables it and the instruments supported by the several brackets 75 thereon with their circuit cords to be handled as a unit.

Each bracket comprises a pair of relatively movable arms, preferably spring arms, which are designated 4, and include 80 flanges 5 at their inner extremities, the flanges on the opposing arms extend laterally toward each other and are attached to the supporting arm 3 in the manner shown in Fig. 5 by means of screws 5^a and plates 6, 85 which overlie the abutting ends of the flanges. The latter are seated in depressions in the side face of the arm, the edges of the recesses embracing the bent corners of the spring arms, thus preventing them from 90 working laterally or twisting from beneath the plates 6. Each of the arms 4 is provided with a contact 6 supported by insulating washer 7 and connected by suitable conductors with conducting sleeves 8, arranged on 95 the rear face of the supporting arm 3, and in turn connected to conductors 9 which lead to an instrument, one of which is illustrated at 10. The arms 4 are each provided with outwardly curved portions 11 which embrace 100 the instrument for supporting it, and curved outer ends 12 which permit the instrument to be readily positioned by pushing it between the arms, so as to spread them apart. The spring tendency of the arms causes them 105 to approach each other, to bring the contacts 6 into engagement under normal conditions, and to close the circuit which controls or heats the instrument. When the latter is inserted in the bracket, the arms are spread 110

apart sufficiently to separate said contacts, and in this manner open the controlling circuit, whereby the instrument is cut off from the current supply so that there is no electrical consumption when it is not in use. The operation is an automatic one, and when an instrument is removed from its supporting bracket for operating purposes, its controlling circuit is instantaneously closed and it requires but a few moments to heat the instrument sufficiently so that it is ready for use. The arms 4 are also provided with guard portions or plates 13 which extend in opposite directions from the bracket so as to 10 overlite and underlie the space between the arms that is occupied by the contacts 6, thus affording effective protection for the latter, and preventing an instrument from being moved far enough inwardly between the 15 arms of the bracket to engage the contacts referred to.

It is to be understood that the instrument bracket is not limited in its application to any particular type of instrument but is intended to be adopted in conjunction with any electrical instrument or tool where it is desirable to arrange for opening the electrical controlling circuit during the time that the device is arranged in the bracket and to 25 automatically close the circuit again upon removing the instrument for further operation.

It will be noted that our support is mounted on the door of the mechanism so that the instruments and their connecting wires are moved out of the way when the door is opened; also that the support itself is hollow, affording a means for concealing the wires and is easily kept clean and in a sanitary 30 condition and may be removed when occasion requires.

We claim as our invention:

1. The combination with an electrically controlled instrument and a circuit for governing the same, of a supporting bracket including a pair of spring arms having contacts normally in engagement and forming a part of said circuit, the arms being movable apart to separate said contacts and support the instrument, and guard portions carried by the arms.

2. An instrument support for an electric

controlling apparatus comprising a casing, a supporting arm depending therefrom, a bracket on the support comprising opposed spring arms, contacts carried by the arms, and conductors leading from the contacts to the casing.

3. An instrument support for an electric controlling apparatus comprising a casing and a movable door therefor, a hollow arm depending from the door, conductors leading from the casing through said hollow arm to an instrument, and a bracket on the arm for supporting said instrument comprising a pair of contacts adapted to close the electric circuit automatically when the instrument is removed.

4. An instrument support comprising two opposed spring arms, coöperating contacts on the arms, one supported on each of said arms and insulated therefrom, and separate conductors extending from the contacts rearwardly between the arms.

5. An instrument holder comprising a hollow support, spring arms secured to the support having free outer extremities, co-operating contacts on said arms, and conductors extending rearwardly from said contacts and through the support.

6. The combination with an electrically controlled instrument and a circuit therefor, of a bracket for supporting the instrument and having contacts forming a part of said circuit, and means in the path of the instrument for preventing the instrument from forming a short circuit by engagement with said contacts when it is inserted in the bracket.

7. An instrument support for an electric controlling apparatus comprising a casing, a hollow arm depending therefrom having a horizontal portion, a plurality of instrument supporting brackets comprising spring arms mounted on the support and carrying contacts, conductors leading from the contacts through the arm and coöperating plug or jack terminals for said conductors arranged on the arm and casing.

OSCAR H. PIEPER.
ALPHONSE F. PIEPER.
